UNITED STATES PATENT OFFICE

FRANK M. QUINSLER, OF CHICAGO, ILLINOIS

POWER DRIVEN PLANE

Application filed May 2, 1930. Serial No. 449,248.

This invention relates to certain novel improvements in power driven planes and has for its principal object the provision of an improved construction of this character which will be highly efficient in use and economical in manufacture.

Among the several objects of the invention is the provision of a plane of this character which is electrically operated for planing or smooth finishing a surface of wood or the like by a plane operated in a horizontal plane from a vertically disposed operating mechanism thereby to more effectively accomplish the work of a plane of this type.

15 A still further object of the invention resides in the novel arrangement for adjusting the plane cutting mechanism in a proper position for effective operation upon the work.

20 A still further object of the invention resides in the simplicity of arrangement of parts which afford expeditious assembly of the several parts making up the device.

Other objects will appear hereinafter.

The invention consists in the novel combination and arrangement of parts to be herein-after described and claimed.

The invention will be best understood by reference to the accompanying drawings, showing the preferred form of construction 30 and in which:

Fig. 1 is a top plan view of the invention;

Fig. 2 is a sectional detail view of the same taken substantially on the line 2—2 of Fig. 1;

Fig. 3 is an end elevational view of the invention;

Fig. 4 is a fragmentary bottom plan view of the invention; and

Fig. 5 is a fragmentary sectional detail view of the invention taken substantially on the line 5—5 of Fig. 2.

To accomplish the many objects of this invention I provide a power driven plane which includes a base 10 on which a body 11 is mounted. This body 11 includes a sleeve 12 of a split type structure for reasons herein-after set forth. This sleeve 12 adjacent the split end 13 is provided with oppositely disposed lateral ears 14 connected together by means of a screw or bolt 15 whereby the sleeve 50 will be clamped about a motor housing 16 of

a motor 17 of electrical construction including an armature 18 having its shafts 19 and 20 journaled in suitable bearings 21. The motor 17 is arranged in an inverted position so that the shaft 20 thereof will project downwardly and exteriorly of the housing 16. The motor 17 may be of any approved structure and is connected in circuit with a suitable source of electric energy by means of conductor wire 22 in which is incorporated a switch 23 of any approved construction. The motor housing 16 is mounted within the sleeve 12 and clamped therein by means of a screw 15.

Referring to Fig. 5 of the drawings, it will be seen that an edge portion 24 of the motor housing is provided with a cam edge 25 adapted to engage pin 26 supported by the body 11. This arrangement is such that by relieving the clamped condition between the sleeve 12 and the motor housing 16 the motor may be elevated or lowered vertically for reasons hereinafter set forth. This is accomplished by rotating the housing 16 so that the cam edge 25 will ride upon the pin 26 and elevate or lower the housing according to the direction of rotation.

As shown, the forward end portion of the base 10 terminates a predetermined distance from the forward end portion of the body 11 so that an opening 55 is provided between the end of the base 10 and a shoe 27, through which opening 55 project the cutting or planing elements to be presently described.

This shoe 27 is capable of vertical adjustment and this is accomplished by providing as an integral part of the shoe a stud 28 which extends upwardly through a boss 29 formed at the forward end portion of the body 11. Threaded upon this stud 28 is an adjustment cap 30 which bears upon the boss 29 whereby upon rotation of the cap 30 the shoe will be moved upwardly or downwardly. Surrounding the stud 28 is a spring 31 which spring provides a yieldable connection between the shoe and the body 11 whereby when manual pressure is applied to the body 11 in a manner to be presently described the planing elements may be brought into closer contact with the work. This manual pressure may be applied by placing one hand at the for-

ward end of the body 11 as on top of motor housing 17, while guiding and operating the movement of the plane by the other hand by grasping the handle 32 which is secured to the rear portion of the body 11 by suitable screws 33, handle 32 carrying the switch 23 which includes a suitable switch lever 34 whereby to provide expeditious operation of the switch. The motor and cutter may likewise be forced downwardly toward the work, against the action of spring 31, by screwing down the cap 30, or by tilting the body 11 downwardly by pressure on handle 32.

So as to limit the adjustment movement of the cap 30 for adjusting the shoe 27 there is provided by the cap a stop finger 35 which is adapted to engage a pin 36. This will prevent the cap 30 from becoming completely detached from the stud 28.

The motor 17 is of the brush driven type, said brushes being diagrammatically illustrated at 57 and mounted on the shaft 20 of this motor is a suitable fan 37 which is rotatable with the armature 18 whereby to introduce air over the armature through the housing of the motor and out through suitable openings 38 provided for the purpose. This will also permit the blowing out of any fine shavings or dust that might find entrance into the motor.

The planing elements include an arm 39 which is secured to the outer end of the shaft 20 by means of a sleeve 40 connected to the shaft 20 in any suitable manner and threaded into the arm 39 as at 41. This arm 39 at its outer ends, as best shown in Fig. 4, carries the planing elements 42 which include the blade like edges 43 and tapered shank portions 44 which are removably wedged in similarly shaped sockets 45 provided in the arm 39, there being provided on these shanks ribs 46 which are positioned in dove-tailed grooves 47 formed in the sockets 45.

A guiding bar is indicated at 48 and this guiding bar is hingedly supported from the base 10 as at 49. Pivotally connected to this bar 48 as at 50 are adjustment links 51 slotted as at 52 through which projects a connecting nut bearing bolt 53 supported by lateral ears 54 provided by the base.

From the description herein it will be seen that I provide a plane which includes vertically rotatable planing elements operable by a vertically disposed operated shaft driven by a motor of electrical type confined within a housing and provided for vertical adjustment whereby the cutting blades may be readily adjusted toward the work to produce the desired result. This is of importance in one respect in that it enables the operator to adjust the blades so as to shave or plane a very thin strip from the work operated upon. The adjustment of the shoe permits the blades to be properly disposed in operative engagement with the work whereby to assure a

smooth finish in contradistinction to a rough finish should the blades be adjusted too close to the work. In addition to this the parts are such that they may be readily assembled or disassembled for any reason.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. In a power driven plane, a base plate, a body upon said plate providing a sleeve, a motor including a casing confined vertically within the sleeve, means providing vertical adjustment of said casing within the sleeve, a shoe yieldably supported by said body at the forward end thereof, and planing elements rotatably operable by said motor between the shoe and the forward end of the base plate in substantially a horizontal plane.

2. In a power driven plane, a base plate, a body upon said plate providing a sleeve, a motor including a casing confined vertically within the sleeve, means providing vertical adjustment of said casing within the sleeve, a shoe at the forward end of the body, planing elements rotatably operable by said motor between the shoe and the forward end of the base plate in a substantially horizontal plane, and means providing yieldably supporting connection between the shoe and the body.

3. In a power driven plane, a base plate, a body upon said plate providing a sleeve, a motor including a casing confined vertically within the sleeve, means providing vertical adjustment of said casing within the sleeve, a shoe at the forward end of the body, planing elements rotatably operable by said motor between the shoe and the forward end of the base plate in substantially a horizontal plane, and means providing yieldably supporting and adjustable connection between the shoe and the body.

4. In a power driven plane, a base plate, a body upon said plate providing a sleeve, a motor including a casing confined vertically within the sleeve, means providing vertical adjustment of said casing within the sleeve, a shoe at the forward end of the body, planing elements operable by said motor between the shoe and the forward end of the base plate in substantially a horizontal plane, said first mentioned means including a cam edge provided by the casing, and a pin member provided by the body for engagement with said edge.

5. In a motor driven plane, a base plate, a

- body upon said plate including a vertically extending sleeve, a motor vertically supported within the sleeve, means providing connection between the sleeve and the casing of the motor, a shoe at the forward end of said body, means providing yieldable supporting connection between said shoe and said body, an arm carried by the shaft of said motor and extending substantially transversely of the shaft, planing elements carried by said arm and rotatably operable by said motor between said shoe and the forward end of said base plate, and means providing connection between the planing elements and said arm.
6. In a motor driven plane, a base plate, a body upon said plate including a vertically extending sleeve, a motor vertically supported within the sleeve, means providing connection between the sleeve and the casing of the motor, an arm carried by the shaft of said motor and extending substantially transversely of the shaft, means yieldably supported by and connected to said body at one end thereof, planing elements rotatably operable between the forward end of said base plate and said second named means, and means providing connection between the planing elements and said arm whereby pressure may be exerted upon said body during the operation of said planing elements to yieldably engage said elements with the work.
7. In an electrically driven plane, a base plate, a body providing a sleeve upon said plate, a shoe, means providing yieldably supporting and adjustable connection between said shoe and said body, a motor including a casing mounted in said sleeve, means for effectuating connection between the sleeve and the motor, means for effectuating adjustment of the motor within said sleeve by rotation of said motor, planing elements carried by the shaft of said motor and rotatable between the forward end of said base plate and said shoe, means providing connection between the planing elements and the shaft of said motor, and fan means operable within the casing by said motor.

In testimony whereof I affix my signature.
FRANK M. QUINSLER.
